COIN CONTROLLED APPARATUS FOR DISPENSING MACHINES

Francis C. Du Grenier, Haverhill, Mass., assignor of one-half to Blanche E. Bouchard, Haverhill, Mass.

Application July 22, 1937, Serial No. 155,034

4 Claims. (Cl. 194—63)

This invention relates to coin-controlled dispensing machines and more particularly to the means for handling the coin which is inserted to release the dispensing mechanism, so that the coin will be delivered to the money box, if the package purchased is delivered, or will be returned to the purchaser if the package is not delivered, as, obviously, either the package must be delivered or the coin must be returned.

- 10 Difficulty has been encountered in machines of this type, in that it has been discovered that by pulling out and then pushing back the operating handle very quickly the package will not only be delivered, but the coin would be returned.
- 15 The primary object of my invention is to provide a construction for handling the coin in which the coin will be retained if the package is delivered regardless of whether the operating means is operated quickly, or at normal speed.
- 20 As the means for retaining or for returning the coin must be operated during the time in which the operating device is moved from and returned to its initial position, I have accomplished this object by providing means for retarding the operation of the coin returning means, so that it may not be operated until after the operating device has been returned to initial position, whereby the coin retaining means, which is operated by the package when it is dispensed, will have ample time to operate before the coin returning means can operate.

For a more complete disclosure of the specific means which I employ, reference is now made to the following specification, in connection with the accompanying drawings, in which:

Fig. 1 is a side elevation of the coin handling mechanism which is employed.

Fig. 2 is a detail sectional view taken at line 2—2 of Fig. 1.

40 Fig. 3 is a similar view showing some of the parts in a different position.

Fig. 4 is a detail sectional view at line 4—4 of Fig. 1.

Fig. 5 is a view similar to Fig. 1, showing certain parts in different positions.

Fig. 6 is a detail view of a portion of the coin retaining and coin returning means.

As shown in the drawings, the main operating device consists of a straight bar 10 having a handle at its outer end and a series of gear teeth on its top side arranged in mesh with a gear 12 on the shaft 14. A wheel 16 is mounted on said shaft, and a bell crank lever 18 is pivoted at 19, and one end thereof is engaged in a notch 20 in wheel 16. The opposite end of said lever has a

shoulder 21 which is arranged to engage a shoulder 22 on a locking lever 24, so that if no coin has been inserted and the bar 10 is pulled out, the parts immediately become locked.

If a coin has been inserted and passes the coin testing means, it will lodge on support 25, in the position indicated at X in Figs. 1 and 6, so that, as lever 18 is advanced, it will push the coin against lever 24 and lift it out of locking position, permitting the dispensing operation to be per-

10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

By this movement the coin is advanced to the position indicated at y, in Figs. 1 and 6, in which position it is supported by two pivoted dogs 26 and 28 directly over a vertical partition 30, which separates the coin retaining passage 32 and the coin returning passage 33. When in this position if dog 26 is moved so that it is withdrawn from its coin supporting position, the coin will fall into the passage 32 and pass into the money box, and if the dog 28 is moved, so that it is withdrawn from its coin supporting position, the coin will be returned.

It may be assumed that the package dispensing operation will be performed when the bar 10 has been pulled out to its fullest extent and that a package will be discharged into a passage 34 at the rear side of the machine. Means are provided for operating the dog 26 when a package is discharged into said passage, which consist of a shelf 35, which is pivotally mounted on a shaft 36, and is normally supported in a horizontal position in passage 34 by means of a counterweight 37. A lever 38 is pivoted at 39, and one end of said lever is arranged in engagement with a lug 40 on counterweight 37 and the opposite end of said lever is pivotally connected at 41 to an arm 42 mounted on a shaft 43. In some instances a second shelf 44, indicated in dotted lines in Fig. 1, is mounted at shaft 43, and is normally held in a horizontal position by counterweight 37, through the action of lever 38. A stiff wire 45 is connected to pivot 41 at end of arm 42, and is extended to dog 26, to one arm of which it is pivotally connected.

With this arrangement, when a package falls down passage 34 it will strike on shelf 35, causing it to be swung down and thereby swinging lever 38, so that arm 42 will be swung from the full line to the dotted line position of Fig. 5, thereby pulling wire 45 rearwardly and swinging dog 26 sufficiently to withdraw it from its coin supporting position, so that the coin will fall into the money box. The same action will take place if the shelf 44 is swung downward by a package

which may fall thereon. The package is not intercepted, in either instance, by the shelves 38 or 44, but passes on to a receptacle from which it may be removed by the purchaser, and the parts 5 thus momentarily moved thereby are immediately returned to normal position by the counterweight 37, and a spring 46 attached to dog 26.

The means for controlling the dog 28 comprise a rod 47 having a piston 48 reciprocally movable 10 in a cylinder 49, which is open at one end and closed at the opposite end, except for a leak hole the size of which is regulated by a screw valve 50. A collar 51 is secured on rod 47 and a spring 52 is connected thereto and to the cylinder, and 15 normally acts to hold the rod in the position of Figs. 1 and 2. A collar 54 is also mounted on rod 47, in position to engage one end of dog 28, as shown in Fig. 2. As thus arranged, spring 52 normally holds the parts in the position of Fig. 20 2, in which position the dog 28 is held in an inoperative position. The lever 18 has a projecting lug 55, so arranged that, when the lever is moved from its normal position, after a coin has been inserted, the lug 55 engages collar 51 and pushes 25 rod 47 in the direction to withdraw it from cylinder 49, and thereby moves collar 54 out of engagement with one arm of dog 28 and into engagement with the other arm thereof, thereby moving the dog into its operative, or coin supporting position, as shown in Fig. 3, so that, when 30 the coin is discharged from support 25, it will be intercepted by the dogs 26 and 28 and held in position y of Fig. 6. If dog 26 is operated by the falling package, the coin will be retained as 35 before described, but if no package is delivered the coin will be retained in position y until the lever 18 is returned to normal position and the return of rod 47 to normal position is permitted. The return movement of rod 47 is, however, re-40 retarded by the piston 48, the speed at which it is returned depending on the adjustment of valve 50, which permits the air to escape slowly from cylinder 49, so that if the operating bar 10 is pulled out and pushed back quickly, the shelves 36 45 or 44 will have ample time to operate dog 26 and discharge the coin into the money box, before the dog 28 is moved to its inoperative position, and this may occur some time after the operating bar has been returned to initial position.

50 If no package is discharged, when the rod 47 is moved back to its initial position, the dog 28 will be moved to its inoperative position permitting the coin to be returned.

With the above described arrangement it will 55 not be possible to secure the package and the return of the coin by pulling out and pushing back the operating bar very quickly, as the package will have ample time to fall and operate the dog 26 before the rod 47 will be permitted by the dash 60 pot to move back sufficiently to operate the dog 28.

I claim:

1. In a coin controlled dispensing machine having coin-retaining and coin-returning passages with the entrances thereto arranged adjacent each other, an operating device for dispensing a package when moved from its initial position, coin-released locking means normally acting to prevent operative movement of said device, a support arranged to receive a coin when inserted, means arranged to be actuated by said operating device to move the coin from said support to release said locking means and deliver the coin to one of said passages, a pair of dogs arranged to support the coin at the entrance to said passages when delivered thereto, and so arranged

that when either is moved from its supporting position the coin will be delivered to the corresponding passage, controlling means for one of said dogs arranged to be moved from coin-supporting position by a package when dispensed, to discharge the coin into the coin-retaining passage, and means for moving the other dog into coin-supporting position when said operating device is moved from initial position and for moving it from coin-supporting position when said device is returned to initial position.

2. In a coin controlled dispensing machine having coin-retaining and coin-returning passages with the entrances thereto arranged adjacent each other, an operating device for dispensing a package when moved from its initial position, coin-released locking means normally acting to prevent operative movement of said device, a support arranged to receive a coin when inserted, means arranged to be actuated by said operating device to move the coin from said support to release said locking means and deliver the coin to one of said passages, a pair of dogs arranged to support the coin at the entrance to said passages when delivered thereto, and so arranged that when either is moved from its supporting position the coin will be delivered to the corresponding passage, controlling means for one of said dogs arranged to be moved from coin-supporting position by a package when dispensed, to discharge the coin into the coin-retaining passage, means for moving the other dog into coin-supporting position when said operating device is moved from its initial position and means independent of said operating device for moving the dog from coin-supporting position when the operating device is returned to initial position.

3. In a coin controlled dispensing machine having coin-retaining and coin-returning passages with the entrances thereto arranged adjacent each other, an operating device for dispensing a package when moved from its initial position, coin-released locking means normally acting to prevent operative movement of said device, a support arranged to receive a coin when inserted, means arranged to be actuated by said operating device to move the coin from said support to release said locking means and deliver the coin to one of said passages, a pair of dogs arranged to support the coin at the entrance to said passages when delivered thereto, and so arranged that when either is moved from its supporting position the coin will be delivered to the corresponding passage, controlling means for one of said dogs arranged to be moved from coin-supporting position by a package when dispensed, to discharge the coin into the coin-retaining passage, means for moving the other dog into coin-supporting position when said operating device is moved from its initial position and for returning it to inoperative position when the operating device is returned to initial position, and means for retarding the return thereof to inoperative position, to permit the operating device to be returned to initial position in advance of the movement of the dog from coin-supporting position.

4. In a coin controlled dispensing machine having coin-retaining and coin-returning passages with the entrances thereto arranged adjacent each other, an operating device for dispensing a package when moved from its initial position, coin-released locking means normally acting to prevent operative movement of said device, a support arranged to receive a coin when in-

serted, means arranged to be actuated by said operating device to move the coin from said support to release said locking means and deliver the coin to one of said passages, a pair of dogs ar-
5 ranged to support the coin at the entrance to said passages when delivered thereto, and so ar-
ranged that when either is moved from its sup-
porting position the coin will be delivered to the corresponding passage, controlling means for one
10 of said dogs arranged to be moved from coin-
supporting position by a package when dis-
pensed, to discharge the coin into the coin-re-

taining passage, means for moving the other dog into coin-supporting position when said operating device is moved from its initial position and for returning it to inoperative position when the operating device is returned to initial position, and a retarding device for controlling the speed at which the dog is returned to inoperative position arranged for adjustment to permit the operating device to be returned to initial position in advance of the return of the dog to inopera-
5 10 tive position.

FRANCIS C. DU GRENIER.
